FIGURE 1 is a perspective view of a picture frame or similar article showing my new design;

FIGURE 2 is a plan view thereof;

FIGURE 3 is a side elevational view towards the edge of the frame having the longest dimension;

FIGURE 4 is a section of the frame taken along line 4—4 of FIGURE 2;

FIGURE 5 is a section of the frame taken along line 5—5 of FIGURE 2;

FIGURE 6 is an end elevational view towards the edge of the frame having the shortest dimension;

FIGURE 7 is a section of the frame taken along line 7—7 of FIGURE 6; and

FIGURE 8 is a section of the frame taken along line 8—8 of FIGURE 6.

The characteristic feature of our design resides in the wide flat angled flanges at the mid-points and narrowing towards the corners, thereby causing the corners to be of deeper depths than the mid-points all as shown.

We claim:

The ornamental design for a picture frame or similar article, as shown and described.
